[57] CLAIM

The ornamental design for an armoire, as shown and described.

DESCRIPTION

FIG. 1 is a top plan view of an armoire showing my new design;

FIG. 2 is a left front top perspective view as seen when in use;

FIG. 3 is a front elevational view thereof; and,

FIG. 4 is a left side elevational view as seen when in use, the right side elevational view being a mirror image thereof. The rear forms no part of the claimed design.
